Des. 176,928
Patented Feb. 14, 1956

176,928

ADJUSTABLE TABLE

Charles S. Puglia and Chatham C. Clark,
Elizabethtown, N. C.

Application April 21, 1955, Serial No. 35,616

Term of patent 14 years

(Cl. D33—14)

Fig. 1.

Fig. 2.

Fig. 3.

Fig. 1 is a perspective view of an adjustable table embodying our new design, with the table adjusted to full height;

Fig. 2 is a perspective view thereof in a partially raised position; and,

Fig. 3 is a view of the table in fully lowered position.

We claim:

The ornamental design for an adjustable table, substantially as shown and described.
